UNITED STATES PATENT OFFICE.

RALPH F. ROGERS, OF CHICAGO, ILLINOIS.

DESIGN FOR A MOTOR-CYCLE CARRIAGE-BODY.

43,678.

Specification for Design.

Patented Mar. 4, 1913.

Application filed January 13, 1913. Serial No. 741,886. Term of patent 14 years.

To all whom it may concern:

Be it known that I, RALPH F. ROGERS, a citizen of the United States, residing at Chicago, in the county of Cook, State of Illinois, have invented a new, original, and ornamental Design for a Motor-Cycle Carriage-Body, of which the following is a specification, reference being had to the accompanying drawing, forming a part thereof.

The figure is a perspective view showing my new design.

I claim:

The ornamental design for a motor cycle carriage body, as shown.

RALPH F. ROGERS.

Witnesses:

JAMES R. OFFIELD,
SADIE M. RYAN.
